United States Patent Office

Des. 185,738

Patented July 28, 1959

185,738

BEVERAGE DISPENSER UNIT

Richard T. Cornelius, Minneapolis, Minn.

Application February 6, 1957, Serial No. 44,775

Term of patent 14 years

(Cl. D2—3)

The figure is a front perspective view of a beverage dispenser unit showing my new design.

The back of the beverage dispenser unit is substantially plain and substantially flat.

I claim:

The ornamental design for a beverage dispenser unit, as shown and described.
